UNITED STATES PATENT OFFICE

MARTIN A. BARBER, OF CLEVELAND, OHIO, ASSIGNOR TO CONSOLIDATED CONNECTOR PATENT CORPORATION, OF WILMINGTON, DELAWARE

AUTOMATIC TRAIN PIPE CONNECTER

Application filed March 9, 1929. Serial No. 345,806.

This invention relates to automatic train-pipe connectors and more particularly to means for facilitating the interengagement of coacting heads which utilize a lock such as that illustrated in Patent No. 1,518,380, which was issued to me December 9th, 1924. Briefly, the lock illustrated in such patent, comprises inter-engaging shoulders on the projection or horn, and on the coacting recess adjacent the lowermost bearing surface between the two coacting parts. The heads, while uncoupled, are normally tilted slightly upwardly. This slight upward inclination facilitates coupling of the heads. If for any reason one head should be substantially lower than the other, or if the adjustment of the normal inclination should become modified and should result in a downward inclination of the head, then there is apt to be a binding action between the coacting heads which would tend to prevent the accomplishment of the proper locking action.

The lock illustrated in my previous patent is valuable however, as it insures automatic locking action between coacting connector heads without the necessity for the use of locking members, which move relatively to the head.

An object of the present invention is to permit the use of a lock illustrated in my patent, and to insure an automatic coupling and locking action of coacting heads, notwithstanding any variation in the normal inclination of the uncoupled heads. In this connection, my invention is directed toward a construction which is well adapted for use in existing connectors and which possesses characteristics of simplicity and ruggedness of construction.

The preferred means for carrying out my invention is illustrated in the drawings wherein Fig. 1 is a side elevation of automatic connectors embodying my invention on the adjacent ends of two cars in the act of being coupled or uncoupled; Fig. 2 is also a side elevation of the connectors but showing their relative position when the cars are coupled; Fig. 3 is a top plan view of two connected heads; Fig. 4 is a vertical section taken on the line 4-4 in Fig. 3; Fig. 5 is a front elevation of one of the heads, and Fig. 6 is a sec-

tion similar to that shown in Fig. 4 and illustrates two connectors being coupled as one head is inclined downwardly from the normal position.

In the various figures, 10 indicates a railway car having the usual coupler 11, and bracket 12 extending downwardly from each coupler and supporting an automatic connector. The connector shown, comprises a head 13 which has a shank extending rearwardly therefrom, and which is mounted in the bracket upon a universal joint indicated in general at 15. A spring 16 surrounds the shank and functions to urge the head forwardly of the bracket. The head is normally tilted slightly upwardly, as is shown in Fig. 1, by means of a rod 9 which extends between the head and bracket, and by a stop block 17, which is mounted on the shank and is disposed adjacent the rear face 18 of the bracket.

Each head has a projection, or horn 20, and a recess 21 in the form of a conduit which are disposed on opposite sides of the head, while vertically aligned ports 22, 23 and 24 are disposed in each head between the projection and recess. The lower port is adapted to be connected to a steam pipe 25, while the other ports are adapted to be connected to the signal, and air brake lines respectively, in the usual way.

To effect a locking action between connected heads, the bottom bearing surface of each projection has a shoulder 26 while the coacting surface on the recess has a shoulder 27. A more detailed explanation of the lock arrangement and connector action is illustrated, described and claimed in my patent heretofore referred to.

In the lock shown and described, it is obvious that an inter-engagement of the heads can be readily made if the heads are tilted slightly during the coupling operation. Such tilted position permits the locking shoulders to clear each other during the coupling movement, and then to move into locking engagement when the coupling operation is completed. If for any reason, however, either head should be lowered from the normal position, then the top surfaces of the horn and the coacting recess are apt to be

brought into engagement before the shoulder on the horn can enter the recess, as is shown in Fig. 6. A continued coupling movement will then cause a binding action upon the 5 bottom bearing surfaces of the horn and recess. This may prevent connection between the heads.

To alleviate this condition, I provide a yieldable member adjacent the top inter-engaging surfaces. In the drawings, the yieldable member takes the form of a ball 30, which is preferably mounted in the top wall of the recess, and is normally urged outwardly by a spring 31. A cap screw 33 encloses the opening in which the ball is mounted and holds the spring in place. In the extended position, the ball projects beyond the bearing surface 34 of the recess, and is adapted to be engaged by the inclined surface 35 of the coacting horn, during the coupling operation.

After the heads are coupled, the springs 16 tend to hold them in connected relationship. If the pressure in the steam pipe should become excessive however, there is a tendency for the heads to separate at the bottom and to pivot about the top. This tendency is overcome by the binding action which takes place at the bottom bearing surfaces adjacent the locking shoulders. By placing the shoulders above the axis of the steam pipe, as shown in the various drawings, the parting resistance is increased proportionately to the parting effort.

It is thus apparent, if the horn of one head should engage the recess of a coacting head on the upper bearing surface, before engagement is made on the bottom surface during the coupling operation, the spring pressed member will yield sufficiently to permit the shoulder at the bottom of the horn to move into the recess on a coacting head. It is also evident that the yieldable feature will permit the coacting shoulders to interlock, 45 as soon as the heads are moved to the final connected position.

I claim:

In an automatic train pipe connector, the 50 combination with a pair of connector heads, each having a guiding projection and a conduit, a support for each head, means associated with the support for holding the heads in a predetermined angular position with reference to the support for coupling purposes; interengaging shoulders on the two heads for locking them together, and yieldable means carried on one of the heads opposite the shoulder for permitting the heads to 55 slide together if they approach at any but the predetermined angle.

In testimony whereof, I hereunto affix my signature:

MARTIN A. BARBER.
